(57) **CLAIM**

The ornamental design for a wall protector, as shown and described.

DESCRIPTION

FIG. 1 is a front, top isometric view of a wall protector.

FIG. 2 is a rear, bottom isometric view thereof;

FIG. 3 is a front elevational view thereof, the rear elevational view being a mirror image of FIG. 3;

FIG. 4 is a bottom plan view thereof;

FIG. 5 is a sectional view taken along the line indicated in FIG. 4;

FIG. 6 is a top plan view thereof; [and,]

FIG. 7 is a sectional view taken along the line indicated in FIG. 6[1];

FIG. 8 is a front, top isometric view of a wall protector;

FIG. 9 is a rear, bottom isometric view thereof;

FIG. 10 is a front elevational view thereof, the rear elevational view being a mirror image of FIG. 10;

FIG. 11 is a bottom plan view thereof; and

FIG. 12 is a top plan view thereof.

Broken lines in dash-dot illustrate unclaimed portions of the wall protector.

Broken lines in dash-dot illustrate unclaimed boundary lines between claimed and unclaimed portions of the wall protector.

1 Claim, 12 Drawing Sheets

Matter enclosed in heavy brackets [ ] appears in the original patent but forms no part of this reissue; matter printed in italics indicates the additions made by reissue.
